James S. McCurdy, of Brooklyn, N. Y.

Assignor to

John M. Myers, of New York City

Letters Patent No. 1110. Dated June 14, 1859.

~~~~~

The schedule referred to in these Letters Patent and making part of the same.

~~~~~

To all to whom these presents shall come:

Be it known that I, James S. McCurdy, of Brooklyn, in the County of Kings and State of New York, have invented and made and applied to use a certain new and ornamental design for the Arms of Sewing Machines, and I do hereby declare the following, to be a full, clear and exact description of the said Design, reference being had to the annexed drawing, in which

Fig. 1. is a side view of the arm used to carry a pressure foot, and

Fig. 2. is a cross section of the same at the line a. a. —

Fig. 3. is a side elevation of the vibrating arm carrying the needle, and

Fig. 4. is a cross section thereof at b. b. —

The ornamental design of these arms is a compound curve as shown, the arm, Figs. 1 & 2, being ornamented and made lighter by the open work and ornamental connections between the top and bottom parts:

The other arm Figs. 3 and 4, being ornamented with a rib on its side curved as represented. To the rear of the arm Figs. 1 and 2, ornamental projections c. c. may be provided for carrying a spool. —

2

Dec 1110

I having thus described my said ornamental Design for the arms of serving machines what I claim as new and desire to secure by Letters Patent is the ornamental design of the arms for serving machines as shown in the drawing.

In witness whereof I have hereunto set my signature this Twenty fourth day

of May 1859.

Ex'd   Witnesses.
G.M.P.   Samuel W. Serrall.
Thos. G. Howard.
